UNITED STATES PATENT OFFICE.

CLIFFORD J. TOMLINSON, OF WEST ALLIS, WISCONSIN.

ROTARY KILN.

Application filed October 30, 1923. Serial No. 671,774.

To all whom it may concern:

Be it known that I, CLIFFORD J. TOMLINSON, a citizen of the United States, and a resident of West Allis, in the county of Milwaukee and State of Wisconsin, have invented a new and improved Rotary Kiln, of which the following is a full, clear, and exact description.

This invention relates to improvements 10 in rotary kilns, particularly to a rotary kiln for burning lime of that general type in which the kiln is located at an inclined position, and consists of a long cylinder mounted to rotate. With this type of kiln 15 the raw material is fed to the upper end of the kiln and travels by gravity as the kiln rotates to the discharge end, being meanwhile subjected to the action of a treating flame injected at the lower discharge 20 end of the kiln. A large proportion of the heat absorbed by the raw material in its passage through the kiln is obtained by its contact with the heated kiln lining passing under the raw material as the kiln rotates.

An object of this invention is to provide a kiln provided with a novel form of lining so constructed, particularly in regard 30 to what may be termed special projections shaped and arranged to constitute combing means relative to the material, that a maximum heating surface is presented to the raw material passing therethrough, and a lining which will serve to stir the raw material, without great mechanical impetus to 35 the comparatively slow gravity travel of the material axially of the kiln and without a bodily lifting of the material to such a height above the bottom of the kiln as 40 to result in noticeable up-liftings and down-droppings of masses of the material, that is to say, a lining which will truly comb through all or most of each of the masses of material in the paths of said projections, 45 and thus, more intimately than heretofore, bring all the material into contact with the lining, and with the heated projection-surfaces thereof, particularly during passage 50 of the material from the upper to the lower end of the kiln.

I have suggested that the kiln was primarily intended for burning lime, but it is to be understood that another important object of the invention is to provide a kiln of peculiar advantage in cement burning.

In burning cement, raw material is introduced into the kiln in powdered form and flows through the kiln much in the manner of a liquid, traveling faster than granular material would travel; in other words, the raw material tends somewhat to run down the trough formed by the inclination of the cylindrical shell rather than strictly to follow the helical path theoretically determined by the rotation and inclination of the shell. In the burning zone of the kiln where the matter has attained granular form, the forward movement of the material is greatly reduced and it is customary to limit the rate of rotation of the kiln because of the tendency of the raw material to travel faster than it should.

Yet another object of this invention, therefore, is to provide a kiln which will retard the movement of the powdered cement and increase the time of treatment of the same, at the same time allowing an increase in the rate of rotation of the kiln. This increase in the rate of rotation will help to clear the burning zone of the kiln 80 of its load of clinker, which as heretofore mentioned, greatly reduced the space for flame in the burning zone, and consequently, the capacity of the kiln. At the same time the increased rate of rotation will result in 85 an increase of heat transference by means of the contact of the raw material and the kiln lining.

As the term "lining" has been hereinabove employed, such term has been used 90 in the sense of including, as well, the projections characteristic of the comb essentially provided by the present invention, but from now on, and particularly in the claims annexed, the term "lining" will be 95 used as meaning the usual fire-brick or other suitable refractory lining as constituting a separate element from the element constituted by the arrangement of inwardly presented projections comprising the combing 100 means.

This distinction must here be clearly made, because another important object of the invention is the provision of such lining of a material having a different heat-absorptive character than the material of which the combing projections are made, that is to say, a material which is rather resistant than otherwise to the ready absorption of heat and consequently to the ready 110

2

delivering of such heat by conduction or radiation to a contiguous or adjacent substance. Preferably, such material is also a highly refractory one. Since, otherwise stated, the object of the invention here being considered is so to construct the combing projections that, on leaving behind the combed material, they will absorb the maximum amount of heat from the longitudinal flame at the upper central portion of the kiln, will lose as little of this heat by conduction as possible to the kiln lining before being again combed through the low-lying material, and will give up as much of this heat by conduction as possible to said material while again combing through the same, an important object of the invention is to provide such lining of a material substantially heat-absorptive and to provide such projections of a material considerably more heat-absorptive than the lining.

A further object is to provide a kiln lined and interiorly equipped in such a manner that not only a greater number of heated surfaces are presented to the material passing therethrough, but a greater number or rather a greater total area of heating surfaces, to wit, heating surfaces of said combing projections, are subjected to the action of the flame without materially obstructing the flow of heating gases through the kiln. To this end, each combing projection is preferably elongate in or substantially in the direction of rotation of the kiln, and preferably includes a forward cutting edge, this edge preferably sloped rearwardly from root to crest of the projection,—such sloping, I have discovered, acting also considerably to increase the efficiency of the projections as pure combing rather than lifting or combing and lifting instrumentalities relative to the material being treated; and each projection, thus preferably or otherwise constructed, further includes at least one edge-following face of rather large area arranged transverse or substantially transverse to the axis of rotation of the kiln, so as to meet the flame substantially broadside on. Remembering again that the projections are essentially combing elements, such face, it will be seen, may be rather appropriately also designated as a plowing face, or a face which sweeps through the material without lifting the same to a sufficient height above the bottom of the kiln so as subsequently to drop any of the material or enough of the material through what may be termed an air-path, as is characteristic of the lifter projections of the prior art, to result in any appreciable loss of the stirred material following subjection of small portions or particles thereof to the blast of the flame. And thereby a very important object of the invention is attained, which is to obviate the really con-

siderable loss of material heretofore encountered in all kilns equipped with projections which raise portions of the material and drop the latter transverse to the line of travel of the flame. It will be apparent that in the case of my invention the fine powdered material being treated, will pile up somewhat before and around the plow or comb, and then, as the plow forces its way through the mass, this pile will be constantly forming and running past the plow in intimate contact with its hot plowing, flaring surfaces, and continue to do so until the plow passes up out of the mass without lifting the same. Each projection of the prior art, being without these plowing surfaces, segregates the mass of material being treated in front of the lifting surface, which stays there until such material is lifted clear of the rest and moved across the path of the flame and a large part blown out of the kiln by the gases passing through the same, while the mass of material in the lower portion of the kiln that is not lifted, will be constantly cascaded from the sides or ends the same as that material which is lifted is cascaded from the top, so that the material cascaded from the sides or ends cannot come into intimate contact with the lifter, thereby completely failing to attain the object of the present invention.

With these and other objects in view, the invention consists in certain novel features of construction, and combinations and arrangements of parts as will be more fully hereinafter described and pointed out in the claims.

This application is a continuation in part of application Serial No. 561,261, filed May 16, 1922.

In the accompanying drawings,

Figure 1 is a perspective view of a kiln embodying my invention, with parts of the upper end of the kiln broken away to expose the kiln lining and a number of the projections.

Figure 2 is a fragmentary interior plan view showing a portion of the lining, showing more clearly the arrangement of the projections as at present preferred; the arrows of Figures 1 and 2 corresponding in direction.

Figure 3 is a perspective view of one of the lining bricks of Figures 1 and 2, this brick including a combing projection as an integral portion thereof.

Figure 4 is a similar view illustrating a slight modification of the form of brick shown in Figure 3, and with the brick wholly comprising such projection.

Figures 5 to 12, both inclusive, show somewhat diagrammatically, the arrows here corresponding to those of Figures 1 and 2, various possible modifications of the cross-sectional and inclinational characteristics of

combing projections which may be employed according to the invention.

Figure 13 is a transverse section through the kiln, but showing merely one of the projections intersected by the plane of the section, and showing that projection combing through the material in the bottom of the kiln.

Figure 14 is a fragmentary view, being substantially a section on the line 14—14 of Figure 13, showing the action of each projection relative to the material combed, it being noted that the showing of the projection here corresponds to the showings of the projections of Figures 5 to 12.

Figure 15 is a view similar to Figure 13, but showing graphically what occurs when other than a combing projection is employed.

Figure 16 is a view similar to Figure 14, but taken substantially on the line 16—16 of Figure 15.

Referring in detail to the drawings, and first to Figures 1, 2, 13 and 14, my improved kiln consists of an elongated cylindrical body portion 1 mounted to rotate in any approved manner upon a plurality of supports 2. This kiln is primarily intended for the burning or treating of lime which is introduced into the upper end of the same and fed by gravity toward the lower end as the kiln rotates.

A treating flame is injected into the lower end of the kiln to treat the raw material as it passes therethrough; the manner of treating the raw material, however, is conventional and I have not shown any means for doing so.

The kiln is provided with a lining as hereinabove defined, or lining proper 3^a, and a plurality of inwardly directed combing projections 4. Such lining equipment may be formed of a plurality of inlaid bricks 3 integrally carrying projections 4, as shown in Fig. 3, in which case kiln lining and spacing bricks 5 are interposed between the bricks 3, as seen most clearly in Figure 2, or such lining proper may include projection-incorporating bricks 7 as shown in Figure 4 with which suitable lining bricks are interposed and interlocked,—so that a staggered arrangement of the projections 4 is provided upon the inner surface of the cylinder 1. It will, of course, be understood that a strictly staggered arrangement is not essential, as any arrangement which accomplishes the purpose, however irregular the spacing, falls within the present invention. But I prefer to employ a lining proper the elements of which are not integral with the combing projections, and hence I could, for example, well employ the arrangement described just above in connection with a projection-brick like that of Figure 4, since then the brick 7 or equiva-

lent, or the portion thereof constituting the 65 combing element projecting above the interior face of the kiln lining, may be formed of a much greater heat-absorptive material, than the material of which the lining proper is formed, in order to attain the heat-conservation feature of the invention while retaining the material-combing feature thereof.

The projections 4 of Figures 1 to 4 are substantially rectangular in shape, or, to 75 be more specific, are in the form of frustated quadrilateral pyramids. The inclined walls of these pyramids are located at angles to the direction of travel of the projection during rotation of the kiln. Each 80 projection is elongated in such direction, and includes a forwardly presented cutting edge 6 adapted to cut through the material in the cylinder without lifting the same, and the two adjacent faces of the projection have 85 alternately a plowing action to turn over and mix up the raw material 8 engaged, as in Figures 13 and 14, and a broadside-on travel through the flame zone above such material; all to the end that the projections 90 4 not only serve to thoroughly comb the raw material passing through the kiln, but also to present a plurality of heated surfaces to the flame and to the material, and all without lifting the material for subsequent release to drop through space back to the bottom of the kiln.

Referring now to Figures 5 to 12, these views, as will be understood, of course illustrate merely various of the many possible 100 designs for a projection 4 according to the invention; each of the projections shown having peculiar advantages of its own. Assuming them all to be made of the same material, some of them are obviously stronger than others, while some have greater 105 combing efficiency. As will be observed, the projections are not only shaped differently, as to the angles, areas and numbers of the follower surfaces in rear of their cutting edges 6', but in some only of said projections, said surfaces are arranged symmetrically relative to the lines of travel of the projections; in some only of said projections, one of said surfaces is parallel to 110 said line of travel, while in others, all said surfaces, in order to provide but a single plowing surface in rear of the cutting edge, are offset to one side of said line of travel. An example of the kind of projection last 115 referred to is shown in Figure 12, where there are provided two flaring surfaces 7' and 7'', but of which the surface 7' is the only plowing surface. The particular kind of projection selected, as to the characteristics above discussed, will of course depend 120 on whether or not the gravity feed of the material longitudinally of the kiln is to be 125

slightly retarded or advanced by the special combing action of the projections installed; whether or not the flaring surfaces are to be of certain predetermined areas; 5 etc., etc.

The fact that the comb elements illustrated in Figures 5 to 12 are all symmetrical about an axis that may or may not be parallel to the direction of motion (except in the 10 case of Figure 8) is only an inadvertent coincidence, and it will be understood that combs of various other and various asymmetrical shapes may also be employed within the invention. It will also be understood 15 that the number of possible shapes of comb teeth is very great and it would be impossible to show them all.

In operation, the kiln may be heated before the material is introduced therein, so 20 that by the time the raw material reaches the projections 4, they will present heated surfaces to the material aiding greatly in the treatment of the same. The ordinary kiln will be lined with these projections 25 through the upper two-thirds of its length, but, of course, the exact proportion of the lining which is formed with these projections is immaterial and may be infinitely varied in accordance with the work to be 30 treated and the conditions under which the kiln is used.

Further to explain the operation of the invention, it is emphasized that the heat-conservation feature of the invention is accomplished by constructing and arranging 35 the projections so that, on the one hand, they are combed through the material as above described, and on the other, between one such combing and another they are 40 passed through the path of the hot gases and present preferably their broad faces to the flame, such faces being in rear of a distinct cutting edge at the head of each projection, such cutting edge being sloped rearwardly 45 from root to crest of the projection as indicated at 6" in Figure 13. The projections are preferably of a substance with a high heat-absorbing and conducting capacity; while the fire-brick or other lining 50 proper of the kiln must be, on the contrary, insulating to prevent heat being transferred to the outer metal parts of the kiln. The present invention, in providing combing 55 projections, thus does not depend at all upon lifting and showering the material through the flame and solid gases, as heretofore proposed; indeed these lifters or conveyor projections of the prior art are in many cases specially arranged and designed 60 so as not to interfere with the showering of the lifting material across the flame path. Such lifting and showering of the material cause great dust losses, which must be overcome by costly and elaborate dust-col-

lectors. Some of the propelling projections 65 of the prior art, have the disadvantage of protecting the material from the very flame with which it is intended to calcine said material; and such projections have been specially designed so as to present broad surfaces 70 to the material to lift and drop or move the material a considerable distance lengthwise of the kiln. In a word, all the previously proposed lifter or propelling projections have knife or cutting edges only 75 because they are broken spirals for moving the material lengthwise of the kiln, and none have cutting edges to avoid lifting or moving the material, that is, to insure 80 combing the material. The action of a lifter or projection of the kind just referred to is, for the purpose of understanding the present invention more clearly, graphically illustrated in Figures 15 and 16; especially with the latter views compared with Figures 13 and 14. The projection 7 of Figure 13, it will be seen, combs through the material 8 in the direction of the arrow shown, without appreciably lifting any of the material, while both flaring surfaces of 90 the projection immediately in rear of the cutting edge 6", are always in all parts totally changing contact with the material being combed. On the other hand, the lifter projection L of Figures 15 and 16 not only 95 showers the material as indicated in Figure 15 and until said projection reaches the top of the kiln, but while traveling through the material in the bottom of the kiln, establishes and carries ahead of it a compacted mass of the material, as indicated at M in Figure 16; this mass persisting as such during practically the whole passage 100 of the comb through the material and therefore defeating a heat interchange between 105 the projection and the part of the material relative to which said projection and the mass M are moving. Finally, of course, the elongation of the projection L is generally 110 transverse to its direction of travel, if such projection has an elongated cross-section at all, and so the surfaces thereof marked L' in Figure 16 are not at all analogous to the surfaces provided by the projection of the present invention in rear of the cutting edge 115 of that projection.

The fundamental difference between the action of the comb of the present invention over the lifter or lifters of the prior art cannot be too much emphasized. The 120 plowing action characteristic of the present invention piles the material ahead of it naturally, and by so doing utilizes more of the plowing surfaces than would otherwise be the case; whereas such lifters will cascade the material from the top and sides, tending to throw such a material away from the heated surface of the lifter, instead of 125

bringing such heated surfaces, as in the case of the present invention, into the most ideal contact with the material for heat transfer.

5 The present invention has been found to be most valuable in regard to the manufacture of Portland cement; since the previous dust loss, in kilns having projections as illustrated in Figures 15 and 16, and amounting to as much as 30% of the raw material, is practically entirely overcome by employing combing projections according to the present invention. It is well known that the raw cement material must be powdered to the fineness of flour before being fed to the kiln, in order to make the chemical reaction possible. But what has just been said should not indicate that the present invention is not of equal value in the 10 "wet process" of cement manufacture; the projections characteristic of the present invention then being employed only of that part of the kiln where the wet material would not stick to the projections, or where 15 the material is dry enough so that it can be acted upon by the combs.

Numerous slight changes and alterations might be made in the general form and arrangement of the parts described without 20 departing from the invention, and hence I do not wish to limit myself to the precise details set forth but consider myself at liberty to make such changes and alterations as fairly fall within the spirit and scope of 25 the appended claims.

I claim:

1. A rotary kiln of the class described, comprising an arrangement of inwardly presented projections on its inner face, each 30 of said projections being provided with a cutting edge presented in the direction of rotation of the kiln, and each of said projections being provided with a plowing surface adjacent its cutting edge.

2. In a rotary kiln, a refractory kiln lining of inwardly presented projections, each 40 of said projections including a plurality of heat absorbing faces, and each of said projections including a cutting edge presented in the direction of rotation of the kiln, and a flaring plowing surface adjacent the cutting edge, said projections being capable of passing through the matter being heated without propelling the same.

3. A rotary kiln of the class described including an arrangement of inwardly presented projections on its inner face, each 50 of said projections being provided with a cutting edge presented in the direction of rotation of the kiln, and each of said projections being provided with a flaring plowing surface adjacent its cutting edge.

4. A rotary kiln of the class described including an arrangement of inwardly pre-

sented projections on its inner face, each of 65 said projections being provided with a cutting edge presented in the direction of rotation of the kiln, and each of said projections being provided with flaring surfaces adjacent its cutting edge.

5. A rotary kiln of the class described including an arrangement of inwardly presented projections on its inner face, each of 70 said projections being provided with a cutting edge presented in the direction of rotation of the kiln, and each of said projections being provided with flaring surfaces adjacent its cutting edge, said projections being of greater length than width in the direction of rotation of the kiln.

6. A rotary kiln of the class described including an arrangement of inwardly presented projections on its inner face, each of 75 said projections being provided with a cutting edge presented in the direction of rotation of the kiln, and each of said projections being provided with a flaring plowing surface adjacent its cutting edge, said projections being of substantially frustrated pyramidal shape.

7. A rotary kiln of the class described including an arrangement of inwardly presented projections on its inner face, each of 80 said projections being provided with a cutting edge presented in the direction of rotation of the kiln, and each of said projections being provided with flaring plowing surfaces adjacent its cutting edge, said projections being of substantially frustrated quadrilateral pyramidal shape.

8. In a rotary kiln, a kiln lining comprising a plurality of bricks, alternate bricks including inwardly presented projections, each of said projections including a plurality of heat-absorbing faces, each of said 95 projections including a cutting edge presented in the direction of rotation of the kiln, and each of said projections tapering from its base to its inner end and including flared plowing surfaces adjacent its cutting edge.

9. In a rotary kiln, a kiln lining comprising a plurality of bricks, alternate bricks including inwardly presented projections, each of said projections including a cutting edge 105 presented in the direction of rotation of the kiln, and each of said projections tapering from its base to its inner end and including a flared plowing surface adjacent its cutting edge, said surfaces being constructed of a 115 material more heat absorbing than the material of the first-mentioned bricks.

10. A rotary kiln of the class described, including an arrangement of inwardly presented projections on its inner face, each of 120 said projections being provided with a cutting edge presented in the direction of rotation of the kiln and each of said projec-

tions being provided with diverging surfaces adjacent its cutting edge, and one of said surfaces having a greater angle of incidence with the radial axis of the kiln than the other of said surfaces.

11. A rotary kiln of the class described, including an arrangement of inwardly presented projections on its inner face consti-

tuting combing means relative to the material being treated in the rotating kiln, each of said projections being provided with a cutting edge presented in the direction of rotation of the kiln and each of said projections being provided with diverging surfaces adjacent its cutting edge.

CLIFFORD J. TOMLINSON.
